Patented Jan. 26, 1858.

UNITED STATES PATENT OFFICE.

GEO. W. WINDSOR, OF ALLEGHENY, PENNSYLVANIA.

RAILROAD-CAR BRAKE.

Specification of Letters Patent No. 19,223, dated January 26, 1858.

To all whom it may concern:

Be it known that I, GEORGE W. WINDSOR, of the city of Allegheny, county of Allegheny, State of Pennsylvania, have invented 5 a new and useful Improvement in Brakes for Locomotives and Railroad-Cars; and I do hereby declare the following to be a full, clear, and exact description thereof, reference being had to the annexed drawing, forming part of this specification, in 10 which—

Figure 1 represents the underside of a locomotive or car, which is turned over so as to exhibit the several parts of my improved brake. Fig. 2 is a perspective view of the same, right side up, showing the action of the brake on the rails.

In both figures, similar parts are indicated by like letters of reference.

20 My invention consists in the use of a brake for locomotives or railroad cars, constructed as hereinafter described and operating to stop their progress by pinching the rails on which the wheels run, which is effected by 25 means of levers, operated at the will of the brakeman, by means of levers working in the threads of a screw cut on the axle of the locomotive or car.

To enable others skilled in the art to make 30 and use my improved railroad brake I will proceed to describe its construction and operation.

In the drawings *a* is the bed or platform 35 of a locomotive or car, *b*, *b'* are the driving wheels (if a locomotive), *c* is the axle of the wheels *b*, *b'* which being rigidly attached to the wheels in the usual manner, moves with them. On the axle *c* and near to each of its 40 wheels are cut the threads of a double screw *s*, *s'*, the portion of the screw marked *s* turning in one direction, and the portion marked *s'* turning in the reverse direction. The threads of the screw *s*, meet the threads of the screw *s'* forming an acute angle at 45 their point of junction. Immediately under that point on the axle *c* where the meeting of the threads *s* and *s'* of the double screw makes the acute angle, the long arms of the levers *d*, *d'* pass longitudinally over, and 50 at right angles to the axle *c*, resting between the threads of the double screw, the lever *d*, lying between the threads *s* and the lever *d'* lying between the threads *s'*, so that as the axle *c* turns on its axis when the locomotive is moving forward, the threads of the

double screw, turning in opposite directions causes the long arms of the levers *d* and *d'* (which at first were parallel to each other) to diverge and separate. The fulcrum or turning point of the parallel levers *d*, *d'* 60 is at *e* which is a round rod of iron, supported horizontally across the bed of the locomotive by the brackets *f*, *f*. These levers *d*, *d'* are kept in place on their fulcrum rod *e* by small pins *i* passed through the rod *e*. 65 The short arms *g*, *g'* of the levers *d*, *d'* extend downward from the fulcrum rod *e*, just far enough to pinch the upper edge of the rail *h* (see Fig. 2), when the long arms *d*, *d'*, of the levers are forced apart by the action 70 of the double screw *s*, *s'*.

On the axle *c* there are two double screws, (one of which is hidden in Fig. 1, by the driving wheel *b*) and two pairs of levers, one pair adjusted to pinch the rail on one 75 side of the track, and the other to pinch the rail on the other side of the track. Now as the power of the locomotive is applied to the driving wheels *b*, *b'* and they turn the axle *c*, which, by means of the double screws 80 *s*, *s'*, forces apart the long arms of the levers *d*, *d'*, and causes the short arms *g*, *g'* to pinch the rail, it is manifest that the speed of the locomotive will be very soon completely arrested, as the power directly applied to stop the motion is the same which produces it, and is greater than any force applied by hand power by means of the brakes now in use.

It is necessary, of course, so to arrange 90 the pinching levers that they will not be in the way of the rails when the cars are in motion and not desired to be stopped. This I effect by depressing the long arms *d*, *d'* of the pinching levers so that they may not be 95 engaged in the threads of the screw *s*, *s'*, which raises the short arms *g*, *g'* above the top of the rail.

A strong bar *k*, turning on a pivot *n* carries at one end a cross bar *l* which is slit 100 to receive the ends of the long arms of the levers *d*, *d'*, the other end of the bar *k*, projects upward through the platform of the car, so as to be accessible to the engineer or brakeman. A strong spring *p* pressing against the bar *k* keeps the levers *d*, *d'* in place between the threads of the double screw *s*, *s'*, but when the handle of the bar *k* is raised up (in which position it may be fastened by a pin) the cross bar *l*, is pressed 105 110

down and the levers d d' are thrown out of gear with the double screw s , s' , and a band of gum elastic q or other contrivance draws together the levers d , d' .

- 5 When it is desired to apply the brake, the pin supporting the handle of the bar k is withdrawn, the bar k then presses upward the levers d , d' which come in contact with the threads of the double screw s , s' , the 10 angle formed by the meeting of the opposite threads s and s' is precisely between the two levers d , d' which immediately gear into the screw and opening, cause the short arms g , g , firmly to grip the rail.
- 15 This brake needs no hand pressure, as it derives its power, (when applied to a locomotive,) from the driving wheels and when

applied to a car from the momentum of the train.

Having thus described my improved railroad brake what I claim as my invention 20 and desire to secure by Letters Patent is—

The use of a brake constructed as herein-before described, and operating, at the will of the brakeman, by means of levers working 25 in the threads of a screw cut in the axle of the car or locomotive wheels, to pinch the rails on which the wheels travel, and thus retard the progress of the cars.

GEO. W. WINDSOR.
